UNITED STATES PATENT OFFICE.

CHARLES E. ANDERSON, OF CHICAGO, ILLINOIS.

AUTOMATIC FURNACE-REGULATOR.

1,139,095.

Specification of Letters Patent. Patented May 11, 1915.

Application filed February 13, 1915. Serial No. 7,963.

To all whom it may concern:

Be it known that I, CHARLES E. ANDERSON, a citizen of the United States, residing at Chicago, in the county of Cook and State 5 of Illinois, have invented a new and useful Improvement in Automatic Furnace-Regulators, of which the following is a specification.

My invention relates to an improvement 10 in means for automatically regulating the steam-pressure in heating furnaces working under low pressure, by causing relatively low pressure to open the draft and close the check on the furnace and relatively high pressure 15 sure to close the draft and open the check.

In the accompanying drawings, Figure 1 is a view in side elevation of a steam-generating heating furnace, of the sectional-boiler type, equipped with my improved 20 regulator; Fig. 2 shows the regulator as in Fig. 1, but on a larger scale and broken; Fig. 3 is a broken section on line 3, Fig. 2, showing the regulator attached to the boiler, and Fig. 4 is an enlarged section on line 4, 25 Fig. 3, through the collapsible water-receptacle.

The furnace 5, provided with the usual hinged front-draft door or valve 6 and hinged rear-check door or valve 7, has a 30 steam-pipe 8 rising from the top of the boiler 9. This pipe has coupled to it an upper horizontally extending section 8^a, to which is coupled a depending section 8^b threaded about its lower end where it carries 35 a T-head 10 connected by an overflow-pipe 11 with a similar head 12 let into the rising section of the steam-pipe. A threaded coupling member 13 (Fig. 4) screws into the lower end of the head 10 and into the central internally threaded nipple 14 of an upper cap-plate 15 having opposite depending ears 16. A bellows-like receptacle 17, of suitable highly flexible material, preferably thin sheet-copper, is provided with an upper head 18 having a central externally threaded nipple 19 screwing into the nipple 14, whereby the receptacle is carried by the steam-pipe 8. The lower receptacle-head 18^a, which is a counterpart of the head 18, 45 is coupled, like the latter, to a lower cap 15^a, which is a counterpart of the cap 15 and provided with opposite ears 16^a. The corresponding ears 16 and 16^a are pivotally connected at 20; and those on one side of the 50 receptacle are provided with upper and lower lugs 21 and 22, the upper lug car-

rying a pair of set-screws 23 to form stops adjustable for regulating the extent of collapsing the receptacle as hereinafter described. A threaded coupling sleeve 24 screws into the nipple on the lower cap 15^a and carries a T-head 25 having one end plugged by a rod 26 screwed into it and carrying adjustably a counterweight 27. An upwardly-curved pipe 28 extends from the opposite end of the head 25 and terminates in an air-vented water-receptacle 29 provided with an upper lug 30 connected by a chain 31, passing over guide-pulleys, as shown in Fig. 1, with the check-door 7, and a lower lug 32 connected by a chain 33 with the draft-door 6.

The regulator is more particularly designed for use on the low-pressure boilers of household heating furnaces, which carry, 75 normally, about 3 ounces of pressure. As the apparatus is represented in operation in Fig. 1 the relatively high steam-pressure has caused the door 6 to close and the door 7 to open for checking the furnace-fire. This 80 has resulted from the pressure in the pipe 8 being exerted on the water in the collapsible receptacle 17 to force the water through the pipe 28 into the receptacle 29 and thus so increase the gravity thereof against that 85 of the weight 27 as to cause the receptacle 29 to descend, dropping the door 6 and raising the door 7, this movement being permitted by the flexibility of the receptacle 17, which is collapsed along one side to the 90 extent permitted by a respective stop 23 by the pressure of the cap 15^a in turning on the pivots 20, with the descent of the water-weighted receptacle. When the steam-pressure becomes reduced to a predetermined extent, 95 the water-level in the receptacle 29 drops by flow of the water back into the collapsible receptacle, thereby reducing the gravity of the receptacle 29 to an extent which enables the weight 27 to act to raise 100 it on the pivots 20, with resultant collapsing of the receptacle 17 at its opposite side, to the extent permitted by the other stop 23, to open the draft-door 6 and close the check-door 7. Any overflow from the receptacle 17, which may result from its becoming overfilled by water of condensation 105 from the steam, runs back into the boiler through the pipe 11.

The regulator thus described is sensitive 110 and thoroughly reliable in its operation, and of very simple and durable construction.

I realize that considerable variation is possible in the details of construction thus specifically shown and described, and I therefore wish to be understood as not intending, by illustrating a single, specific or preferred embodiment of my invention, to be limited thereto.

What I claim as new and desire to secure by Letters Patent is:—

- 10 1. An automatic regulator of the character described, comprising a collapsible receptacle, pivotally connected caps between which said receptacle is confined, a steam-pipe adapted to be connected at one end with a steam-boiler and leading into said receptacle, an upwardly extending water-pipe secured to the lower cap and communicating with said receptacle, a weight on the lower end of said water-pipe, and a water-receptacle on the upper end thereof.
- 15 2. An automatic regulator of the character described, comprising a collapsible receptacle, pivotally connected caps between which said receptacle is confined, a steam-pipe having a rising section adapted to be connected at one end with a steam-boiler and a downwardly extending section leading into the upper end of said receptacle, an overflow-pipe connecting said pipe-sections,
- 20 30 an upwardly curving water-pipe secured to the lower cap and communicating with said receptacle, a weight on the lower end of said water-pipe and a water-receptacle on the upper end thereof.
- 25 35 3. An automatic regulator of the character described, comprising a collapsible receptacle, pivotally connected caps between which said receptacle is confined, a steam-pipe adapted to be connected at one end with a steam-boiler and leading into one
- 30 40 end of said receptacle, an upwardly curving

water-pipe secured to the lower cap and communicating with said receptacle, a weight on the lower end of said water-pipe and a water-receptacle on the upper end 45 thereof, and a stop-device on said caps near their pivotal connection.

4. An automatic regulator of the character described, comprising a collapsible receptacle, caps secured on the opposite heads 50 of said receptacle, having mutually overlapping ears at which they are pivotally connected together, a steam-pipe having a rising section adapted to be connected at one end with a steam-boiler and a downwardly extending section leading through the upper cap into said receptacle, an upwardly extending water-pipe secured to the lower cap and communicating through the latter with said receptacle, a weight on the 55 lower end of said water-pipe and a water-receptacle on the upper end thereof.

5. In combination with a boiler-equipped furnace, provided with a lower front draft-door and an upper rear check-door, a regulator comprising a collapsible receptacle, pivotally connected caps between which said receptacle is confined, a steam-pipe rising from the boiler and having a depending section leading into the upper end of said receptacle, an overflow-pipe connecting the rising and depending steam-pipe sections, an upwardly extending water-pipe secured to the lower cap and communicating through the latter with said receptacle, a 70 weight on the lower end of said water-pipe and a water-receptacle on the upper end thereof having connections with said doors.

CHARLES E. ANDERSON.
